100,943

DESIGN FOR A TEXTILE FABRIC OR SIMILAR ARTICLE OF MANUFACTURE

John F. Gaul, Jr., Clifton, N. J., assignee to
Botany Worsted Mills, Passaic, N. J., a corpora-
tion of New Jersey

Application December 2, 1935, Serial No. 59,855

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, in which Fig. 1 shows a face view of a piece of textile fabric embodying my design, while Fig. 2 is a diagrammatic face view of the design.

The area contained within the dot and dash lines constitutes one design unit, which unit is repeated in the relation indicated over the entire face of the fabric.

The characteristic feature of the present design resides in a plain base fabric 1 and series of parallel bands or rows 2 extending diagonally over the entire face of the fabric, each of said

rows consisting of a plurality of vertical bars 3 of substantially equal dimensions arranged in raised relation to the base fabric and in staggered relation to the adjacent bars 3 of the same row and being positioned with respect to each other forming units, each of said units having the appearance of two parallelograms 4, 5 having one of their sides partially in common, the sides of said parallelogram being formed by the staggered vertical bars 3, and individual vertical bars 6 separating the adjacent units and arranged in staggered relation to each other and to the bars 3 forming the units, the outer ends of all of said bars gradually merging into the base fabric.

I claim:

The ornamental design for a textile fabric or similar article of manufacture substantially as shown and described.

JOHN F. GAUL JR.
